[57] CLAIM

The ornamental design for a reversible toy car, substantially as shown and described.

DESCRIPTION

FIG. 1 is a top perspective view of a reversible toy car showing my new design;

FIG. 2 is a bottom perspective view thereof;

FIG. 3 is a side elevational view of the side not shown in FIGS. 1 and 2; and,

FIG. 4 is an end elevational view of the end not shown in FIGS. 1 and 2.
